UNITED STATES PATENT OFFICE

SIDNEY B. MERRILL, OF CINCINNATI, OHIO, ASSIGNOR TO THE E. W. VANDUZEN COMPANY, OF CINCINNATI, OHIO, A CORPORATION OF OHIO

CONSTRUCTION OF BELLS

Application filed March 13, 1931. Serial No. 522,390.

In the manufacture of bells, it has been known that the shape, dimensions and relationship of the several parts have an effect upon the tone of the bell. Bells, in general, 5 have a top portion usually of rounded shape, a tube portion and a thickened portion opposite the top and known as the flare. The tube and flare merge into each other and form the configuration which gives the article its 10 familiar bell shape. The thickest portion of the flare is known as the strike. The weight and proportions of the bell, the length and thickness of the tube, and the diameter and weight of the flare and strike all have an effect 15 upon the fundamental tones or the overtones of the bell.

It has hitherto been the universal practice in making a bell to proceed as follows: 20 When the size and weight of a bell for a given fundamental tone has been established, a curve is drawn embodying such dimensions as the length and internal diameter of the tube, the length and internal configuration of the flare, and the general relationship of the two, 25 together with, usually, the largest diameter of the bell. This curve is the basic curve of the bell. It is used to prepare a metallic sweep whereby the drag, or lower portion of the bell mould, may be shaped by a rotary motion of the sweep against the then plastic material of the mould. The drag is regularly the portion of the mould which shapes the interior of the bell. Working from the 30 basic curve, the desired weights of metal are built up outwardly, and when these have been calculated and marked off for the various parts, a new curve is established which is the curve of the outer contour of the bell. A sweep is made to this curve, and the cope of 35 the mould formed thereby. The mold parts are then put together, and the metal cast therein.

It is the primary object of my invention to 40 produce a bell having more desirable tone qualities than bells made as described. It is also my object to provide a new process of making bells and determining their several proportions. These and other objects which 45 will be developed hereinafter or will be apparent to one skilled in the art upon reading

these specifications, I accomplish by that certain construction and arrangement of parts in my novel bell, and by that process of making it of which I shall now describe an exemplary embodiment.

In making my new bell, I first proceed to lay out a fundamental curve, after determination of the various diameters and proportions to give me the desired fundamental and appropriate overtones. This curve may be substantially like the fundamental curves hitherto laid out in making bells and employed as described hereinabove. It may differ from such curves in ways appropriate to the securing of particular combinations of 55 tones and overtones. It will usually be a smooth curve of continuously cumulative curvature in the same direction in the tube and flare portions. Upon consideration it 60 will become apparent that one of my primary 65 objects is to secure the most effective massing of the metal portions with respect to this fundamental curve, and the discovery whence my invention proceeds is that entirely 70 new effects and greatly enhanced tonal values may be achieved by a new massing of the metal portions, quite irrespective of the total mass of the metal at any particular point upon the surface of the bell. In other 75 words, those considerations which have hitherto been effective and have been employed in determining the characteristics of the bell, and the various tonal qualities which proceed solely from the size and diameter of 80 the bell, the proportions of its several parts such as the length of the tube, the diameter of the flare, etc., and the total masses of metal in the particular parts, are not disturbed. In bells embodying my invention the 85 dimensions may be changed and the weights of metal in the several parts may also be changed, varied and calculated as hitherto. The new thing which I have done is to mass the desired weights of metal in terms of the 90 thicknesses represented by the said weights in a new way with reference to the fundamental curve of the bell. Having as hereinabove indicated, laid out my fundamental curve and determined the desired weights of metal at the several points therealong, I re- 95 100

duce these weights to terms of thickness, if thickness has not been the basis of my calculation, and I proceed to lay off these thicknesses transversely to the fundamental curve 5 of the bell in such a way that the fundamental curve bisects lines representing the said thicknesses. This gives me my metallic masses distributed in such a way that half of their weight at any given point lies on 10 either side of the fundamental curve. This procedure would also obviously give me two new curves, one on either side of the fundamental. The configuration of these new curves will not be the same, nor will the configuration of either be the same as that of the fundamental. But both curves will bear a certain relationship to the fundamental as determined by the mass of metal at any given point along the fundamental. One of the 15 curves will represent the contour of the inside of the bell and the other will represent the contour of the outside of the bell.

Thus in Figure 1, I have shown in section, a bell in which the top, the tube and the flare 20 are broadly indicated respectively by the numerals 1, 2 and 3. I have shown in dotted lines, a fundamental curve 4 which has been produced as the result of a determination of the various tonal characteristics desired in 25 the bell. The masses of metal in the bell at any given point along the fundamental curve 4, have also been determined by calculation or otherwise, for the desired characteristics. The inner contour of the bell is 30 represented by a line 5 and the outer contour by a line 6. These lines are curves bearing the aforesaid relationship to the fundamental curve 4, and if any point, such as the point 7 be taken along this fundamental 35 curve, it will be found that the distance 8 from the point 7, to the interior curve 5 of the bell, and the distance 9 from point 7 to the exterior curve 6 of the bell, will be equal, or as nearly equal as is consistent with the 40 45 actual manufacturing conditions.

What is true of the point 7 will be true of all other points along the curve 4.

In manufacturing the bell shown in the drawing, a sweep was, of course, made, corresponding to the curve 5, and another sweep corresponding to the curve 6, and these sweeps used to determine the configuration respectively of the drag and cope of the mould.

The practice of my invention, as plainly 55 understood from the drawing, results in a shape of the bell which will ordinarily appear to the eye different from the shape of bells heretofore constructed upon the same fundamental curve. If the fundamental 60 curve 4 of the bell in my drawing, were used to produce a bell by the old method, the curve 4 would mark the interior contour of the bell, and if the same masses of metal from the several parts were employed, the external 65 diameter of the tube would be somewhat

greater and the external diameter of the flare considerably bigger, there being a much greater external swelling of the strike than there is in my new bell. The exterior curve in the 70 strike portion, had for example, a greater curvature in the old bells than it has in mine. It will be understood that I am not limited to any particular curve as the fundamental 75 for my bell, nor to any particular proportion of the parts or weight or metal at any point along the fundamental curve. And further that in proceeding upon the basis of any given fundamental curve, I may increase or decrease the amount of metal in any particular portion 80 of the bell, or in all parts thereof without departing from the spirit of my invention, providing the weight of metal employed is distributed with reference to the fundamental 85 curve in accordance with my invention.

I have found that the employment of my invention in the construction of bells results in the production of a bell having a truer and more beautiful tone, comprising a more perfect fundamental and more desirable overtones. As compared with bells constructed 90 by the old method to produce the same note, whether the old bells be of the same dimensions and weight of metal or not, my bell is outstanding, and presents a more pleasing sound to the ear. Particularly in view of its 95 truer and more pronounced fundamental and more desirable overtones, my new bell is also especially adapted to the production of carillons.

Such surface ornamentation may be placed 100 upon my bell, of course, as will not interfere with the tone quality thereof, and in most instances it is not necessary to take the amount of the metal contained in the said ornamentation into account in determining the general 105 contour of the bell.

Having thus described my invention, what I claim as new and desire to secure by Letters Patent, is:—

1. A process of producing a bell which comprises determining the size and relationship of the several parts of a bell and producing a fundamental curve, determining the weights of metal in the several parts of the bell, and so proportioning these weights in the finished bell, that the masses of metal will be bisected by said fundamental curve at all points.

2. A process of producing a bell which comprises determining the desired size and relationship of the several parts thereof and establishing a fundamental curve, and so proportioning the masses of metal in the several parts of said bell that said curve if produced in any section of said bell, would be equi-distant at all points from the outer and inner surfaces of said bell.

3. The method of producing a bell which comprises determining the size and relationship of the several parts thereof to produce a desired tone and laying out a fundamental 130

curve, determining the masses of metal in the several parts thereof, and laying out said masses of metal in terms of the thickness thereof at any given point upon said fundamental curve, so that said curve will bisect at all points lines representing the thickness of said metal masses at each point, whereby two new curves are established, one lying on either side of said fundamental curve, and 10 constructing a bell so that said last mentioned curves represent the inner and outer configurations thereof.

4. The method of producing a bell which comprises determining the size and relationship of the several parts thereof to produce a desired tone and laying out a fundamental curve, determining the masses of metal in the several parts thereof, and laying out said masses of metal in terms of the thickness 15 thereof at any given point upon said fundamental curve, so that said curve will bisect at all points lines representing the thickness of said metal masses at each point, whereby two new curves are established, one lying on 20 either side of said fundamental curve, and constructing a bell so that said last mentioned curves represent the inner and outer con-

figurations thereof, by producing a sweep from each of said last mentioned curves and using said sweeps to form respectively the cope and drag of a bell mould.

5. As a new article of manufacture, a bell, 70 the tone of which is determined in part at least by a smooth fundamental line of continuous curvature, and a disposition of the masses of metal in the several parts of said bell, such that said line is at all points equidistant from the inner and outer walls of 75 said bell.

6. As a new article of manufacture, a bell, 80 the tone of which is determined in part at least by a smooth fundamental line of continuous curvature, and a disposition of the masses of metal in the several parts of said bell, such that equal weights of metal at all points lie on opposite sides of said line.

7. As a new article of manufacture, a bell, 85 having a smooth continuous fundamental curve calculated to produce a desired tone, the metal masses of said bell being so disposed at all points that said fundamental curve if produced in said bell, would bisect said 90 masses as to weight and thickness.
